EM 002904243 9/2017

Primary Examiner — Austin Murphy(74) *Attorney, Agent, or Firm* — Saidman DesignLaw
Group, LLC(57) **CLAIM**

The ornamental design for a cartridge, as shown and described.

DESCRIPTION

FIG. 1 is a perspective view of a cartridge showing my new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a perspective view thereof in an alternate position;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

The broken lines illustrate structure or features which form no part of the claimed design.

1 Claim, 14 Drawing Sheets(56)
